(57) **CLAIM**

The ornamental design for a display screen with graphical user interface, as shown and described.

DESCRIPTION

FIG. 1 is a front view of a display screen with graphical user interface showing my new design; and,

FIG. 2 is a front view thereof, the broken line showing of a device forms no part of the claimed design.

The broken line showing of the display screen and text in both views forms no part of the claimed design.

1 Claim, 2 Drawing Sheets
